(57) **CLAIM**

The ornamental design for a light fixture with a sensor module, as shown and described.

DESCRIPTION

FIG. 1 is a bottom-side-front perspective view of a light fixture with a sensor module, showing our new design; FIG. 2 is a top-side-front perspective view of the light fixture with the sensor module of FIG. 1;

FIG. 3 is a right-side elevation view of the light fixture with the sensor module of FIG. 1;

FIG. 4 is a left-side elevation view of the light fixture with the sensor module of FIG. 1;

FIG. 5 is a front elevation view of the light fixture with the sensor module of FIG. 1;

FIG. 6 is a rear elevation view of the light fixture with the sensor module of FIG. 1;

FIG. 7 is a bottom plan view of the light fixture with the sensor module of FIG. 1; and,

FIG. 8 is a top plan view of the light fixture with the sensor module of FIG. 1.

The broken lines shown in the figures depict portions of the light fixture with a sensor module that form no part of the claimed design.

1 Claim, 8 Drawing Sheets(56)
